(57) **CLAIM**

The ornamental design for a grooming tool as shown and described.

DESCRIPTION

FIG. 1 is a top, right, front perspective view of a first embodiment of a grooming tool, according to the new design;

FIG. 2 is a bottom, right, rear perspective view of the grooming tool of FIG. 1;

FIG. 3 is a front view of the grooming tool of FIG. 1;

FIG. 4 is a rear view of the grooming tool of FIG. 1;

FIG. 5 is right side view of the grooming tool of FIG. 1;

FIG. 6 is a left side view of the grooming tool of FIG. 1;

FIG. 7 is a top view of the grooming tool of FIG. 1; and,

FIG. 8 is a bottom view of the grooming tool of FIG. 1.
